UNITED STATES PATENT OFFICE.

ABRAHAM G. FELDMAN, OF CHICAGO, ILLINOIS.

NURSERY SEAT.

Application filed April 14, 1927. Serial No. 183,812.

My invention relates to nursery seats of the portable type, and more particularly to those which are attachable to toilet seats of standard design, and it is my main object to provide an adjunct infant's seat which is safe and comfortable.

A further object of the invention is to make the novel nursery seat collapsible, for facility in shipping and compact storage when not in use.

Another object of the invention is to incorporate in the attachment a self-locking device which is dependable to maintain the seat in extended position while in use.

15 A still further object of the invention is to build the novel seat with a continuous armchair mounting of a non-metallic nature, to save the occupant from the cold touch of metal.

20 A final but nevertheless important object of the invention is to design the novel seat with few and simple parts of a sturdy character, indicative of inexpensive manufacture and durability.

25 With the above objects in view and any others that may suggest themselves from the specification and claims to follow, a better understanding of the invention may be gained by reference to the accompanying drawing, in which—

Figure 1 is a perspective view of the novel nursery seat as positioned for use;

Fig. 2 is a plan view of the showing in Figure 1;

35 Fig. 3 is a perspective view of the seat collapsed, partly in section;

Fig. 4 is a detail section of a locking device, taken on the line 4—4 of Fig. 1; and

40 Fig. 5 is a fragmental perspective view illustrating the collapsing action.

Nursery seats of the type mountable on regular toilet seats, while old in a general sense, have so far attained but little popularity owing to the fact that they do not 45 meet the conditions incident to their use. I have carefully analyzed these conditions, and have designed the present invention with the objects outlined above, whereby to satisfactorily meet the situation.

50 In order that a complete understanding of my invention may be gained, I will refer specifically to the drawings, designating the base of the seat by the numeral 10. The base is of wood, preferably white-enamored 55 to suggest sanitation, and is more or less a smaller replica of the standard toilet seat.

Above the seat base is disposed a rounded back-rest 11 with forward continuations 11^a to serve as arm-rests, these having top portions 11^b of extra width for resting the arms 60 of the occupant more comfortably. Across the front of the back-rest structure is disposed a guarding strap 12 for the occupant, one end of the strap being permanently secured at 13 and the other equipped with a 65 T-buckle 14 which locks in a keeper 15. The latter is arched in a horizontal direction and perforated with a horizontal slot 15^a. The strap and buckle are normally positioned in a vertical plane, and the return twist of the 70 keeper to this plane after its T-head is inserted through the slot 15^a locks the head in the keeper, so that the forcing of the strap by the occupant will not open it.

The back rest is supported on each side 75 by two posts 16 and 17, supplemented by parallel links 16^a and 17^a. The posts are secured by screws 16^b and 17^b to the base 10, and rivets 16^c and 17^c are carried by the links and directed outwardly through the 80 posts, the links having the rivets at medial points whereby to secure a pivotal support thereon. The upper ends of the links are secured to the back-rest by loose rivets 16^d and 17^d. The arrangement of the above 85 parts permits the back-rest to be pushed rearwardly from the position of Figure 1 to that of Figure 3, the links 16^a and 17^a going through a folding action whereby the back-rest is deposited upon the base 10. The 90 assembly is now in collapsed form and makes a compact article for shipping or storing in a handy carton or wrapper while not in use, so as to be out of sight.

When about to be used, the appliance is 95 set in collapsed form upon the toilet seat, and attached to the rear portion of the latter preferably with the aid of a spring clip 18 carried by the attachment as indicated in Figure 3 in a position to engage the rear seat portion referred to. The frontal portion of the attachment may be provided with rubber suction cups 19 on its under side to cling to the frontal portion of the toilet seat when the attachment is weighted and keep 100 the latter in steady position.

To raise the back-rest, the strap 12 may be coupled as indicated in Figures 1 and 2 and used as a handle to pull the back-rest forward after the base has been secured to 110 the toilet seats—or while it is held down with the other hand. As the links 16^a and

17^a unfold to vertical position, this position is made the limit of their travel by cooperating locking elements carried by the links and the posts associated therewith. Thus. 5 each link 16^a, as it approaches the vertical position seats an outwardly-projected bottom lug 16^e in a frontal notch 16^f cut in the corresponding post 16, stopping the link from further progress. A similar action 10 applies to each link 17^a and post 17, except that the lug 17^e of that assembly trips the post and falls into a perforation 17^f therein. To permit the tripping action of each link 17^a, its rivet 17^e is made longer; and the 15 fore part of the lug 17^e is rounded off as indicated at 17^g in Figure 3, to act like a cam and cause the link to separate slightly from the post, providing clearance for the travel of the lug behind the post until it falls 20 into the perforation. A compression spring 17^h is coiled upon the outer section of the rivet to draw the link to the post and maintain the lug 17^e seated in the perforation 17^f. The back-rest is thus locked from collapsing in either direction. However, when 25 the collapsing action is desired, all that need be done is to press the heads of the rivets 17^e inwardly with one of the fingers of each hand, while the thumbs are placed on the 30 arm-rest tops 11^b to bear down on the same. It will be seen that the pressure of the rivets 17^e serves to push the links 17^a apart from the post 17 to an extent sufficient to withdraw the lugs 17^e from the perforations 17^f, 35 so that the links 17^a become unlocked from their posts.

It will be noted particularly in Figure 1 that the lug 16^e of each link 16^a is coextensive with the frontal edge of the link, in 40 view of the frontal position of the notch 16^f in each post 16; but the lug 17^e of each link 17^a is—as is more evident in Figure 3—medially positioned, in view of the corresponding position of the perforation 17^f in each post 17.

A nursery seat is thus had which is of few and simple parts, and whose collapsing and raising actions are easy to understand and manipulate. When the back-rest is up, 50 it furnishes a rest for the occupant's back and arms, and in conjunction with the closed frontal cross strap constitutes a guard on all sides, making the position of the occupant safe. The back and arm rests are 55 of non-metallic material, and are therefore agreeable to contact when the occupant is thinly clad. Also they are of light, flat stock of ample width for comfort; and the special arm-rest mountings provide comfort 60 with the use of a minimum of stock. The locking devices are on the outside of the seat, out of the way of the occupant and are of course too firm for the infant to disengage. When collapsed, the article is of 65 small and compact dimensions, facilitating

shipping and storage in a handy receptacle out of the way when not in use.

I claim:

1. A nursery seat comprising a base, posts rigidly carried by the latter, a body rest above the base, links dropped from the body rest and pivoted intermediate of their ends to the upper ends of the posts and interlocking means respectively on the free ends of the links and in the intermediate portions of 75 the posts.

2. A nursery seat comprising a base, posts carried by the latter, a combined arm and back rest above the base, links dropped from the arm and back rest and pivoted medially of their ends to the posts, and cooperative elements in the links and posts to latch the links against pivotal movement relative to the posts.

3. A nursery seat comprising a base, posts carried by the latter and formed with recesses, a combined arm and back rest above the base, links dropped from the arm and back rest and pivoted medially of their ends to the posts, and lugs carried by the lower 90 ends of the links and adapted to seat in said recesses to lock the links from pivotal movement relative to the posts.

4. A nursery seat comprising a base, posts carried by the latter and formed with recesses, a combined arm and back rest above the base, links dropped from the arm and back rest and pivoted medially to the posts, lugs carried by the lower ends of the links and adapted to seat in said recesses to latch 100 the links from pivotal movement relative to the posts, and spring resisted release devices operative to disengage the lugs from the recesses and unlock the links from the posts.

5. In a nursery seat, a base, an elevated back rest, a post carried by the base and having an intermediate slot, a link hung from the back rest along the post and intermediately pivoted thereto, a lug carried by the link and adapted to seat in said slot to 110 lock the link to the post, and a tension device to hold the link to the post and maintain the lug in seated condition.

6. In a nursery seat, a base, an elevated back rest, a post carried by the base and having an intermediate slot, a link hung from the back rest along the post and intermediately pivoted thereto, a lug carried by the link and adapted to seat in said slot to lock the link to the post, and a spring button incorporated in said link pivot to separate the link from the post when actuated and disengage the lug from the slot.

7. In a nursery seat, a base, an elevated back rest and having a terminal aperture 125 and intermediate slot, a link hung from the back rest, a pivot pin carried intermediately by the link and passed through the aperture in the post and having a terminal head, a lug carried by the lower end of the link 130

and adapted to seat in the slot to lock the link to the post, and a compression spring mounted on said pin between the post and the head to hold the link to the post and maintain the lug in seated condition.

8. A nursery seat comprising a base, posts rigidly carried by the latter, a U-shaped body rest above the base, links dropped from the arms of the body rest and pivoted to the posts whereby the body rest may swing to a position above said base, means for locking the body rest in elevated position the connection of the links and posts being at substantially the same height as the connection of the link with the rest when the rest is collapsed.

9. A nursery seat comprising a base, posts rigidly carried by the latter, a body rest above the base, links dropped from the body rest and pivoted to the posts whereby the body rest may swing to a position above said base, and cooperating means associated with one of said arms and posts and spaced from the pivot connection of the latter for latching the body rest in elevated position and yieldable means for maintaining the parts in latched relation.

10. A nursery seat comprising a base, posts rigidly carried by the latter, a body rest above the base, links dropped from the body rest and pivoted in the posts whereby the body rest may be elevated above said base, and the height of said body rest being greater than the height of said posts whereby the ends of the latter will not be exposed

above the upper edge of the body rest to catch in clothing when the said body rest is in lowered position.

11. In a nursery seat having a base and an elevatable body rest disposed thereon, a post carried by said base, cooperating elements carried by the base and body rest for adjustably connecting the two, said cooperating elements having interengaging portions for supporting the body rest in elevated position, and yielding means for normally holding said portions in engagement.

12. In a nursery seat having a base and an elevatable body rest disposed thereon, a post carried by said base, cooperating elements carried by the base and body rest for adjustably connecting the two, said cooperating elements having interengaging portions for supporting the body rest in elevated position, and the adjustable connecting means of said cooperating elements including a yielding means tending to hold contiguous surfaces thereof in frictional contact and said interengaging portions in cooperative relationship.

13. A nursery seat, comprising a base and a back-rest, pairs of members connecting the base and rest, means secured to one member of each pair and extending through an aperture in the other member of the pair, a head on said means, and resilient means between said head and the apertured member.

In testimony whereof I affix my signature.

ABRAHAM G. FELDMAN.
